[57] CLAIM

The ornamental design for a reading stand for exerciser, as shown and described.

DESCRIPTION

FIG. 1 is a reading stand for exerciser showing our design, an exerciser fragment being shown therein in dotted lines for illustrative purposes only.

FIG. 2 is a side elevational view thereof;

FIG. 3 is a top plan view thereof;

FIG. 4 is a bottom plan view thereof;

FIG. 5 is a rear elevational view thereof; and

FIG. 6 is a front elevational view thereof.
